KNITTING MACHINE

Thomas S. Hayhurst, Belle Harbor, N. Y., assignor
to Max Nydegger, Summit, N. J.

Application April 13, 1944, Serial No. 530,769

16 Claims. (Cl. 66—63)

The present invention relates to an improvement in knitting machines. Objects of said invention have been to provide an improvement in decking mechanism for flat links knitting machines; to provide decking devices which are adapted to operate effectively in automatic knitting machines of the links type; and to utilize an improved decker point construction which can be mounted and controlled to cooperate with a needle of the latch type in a manner to remove stitch loops therefrom and deposit stitch loops thereon regardless of whether the latch is then open or closed.

One embodiment of my invention in a form adapted for use in connection with an automatic multiple flat links knitting machine is described in the following specification and illustrated in the appended drawings in which—

Figure 1 is an end elevation of the right end of a links-links knitting machine embodying the improved decking devices and related mechanisms;

Figure 2, a plan view from the line 2—2 of Figure 1 showing portions of mechanisms positioned rearwardly and at the end of the machine shown in Figure 1;

Figure 3, a horizontal section on the line 3—3 of Figure 1;

Figure 4, a plan view, enlarged, of portions of Figure 2 and with parts removed to disclose details of devices connected with decking;

Figure 5, a fragmentary view in vertical section on the line 5—5 of Figure 4 and showing portions of the decker and racking control devices;

Figure 6, a fragmentary view partly in vertical section on the line 6—6 of Figure 4 and showing portions of the decker and racking control devices;

Figure 7, a fragmentary view partly in vertical section on the line 7—7 of Figure 4 and showing portions of the decker and racking control devices;

Figure 8, a fragmentary view in vertical section on the line 8—8 of Figure 6;

Figure 9, a fragmentary view on the line 9—9 of Figure 3 showing the control link associated with the automatic decker control mechanism;

Figure 10, a fragmentary view on the line 10—10 of Figure 3 showing the control link associated with the automatic widening and narrowing control devices employed in fashioning;

Figure 11, an enlarged fragmentary view in plan of a portion of Figure 3 with parts broken away to show portions of widening and narrow-

ing control mechanisms for fashioning and for corresponding decker point carrier adjustment;

Figure 12, a transverse vertical section on the line 12—12 of Figure 11;

Figure 13, a transverse vertical section on the line 13—13 of Figure 11;

Figure 14, a transverse vertical section on the line 14—14 of Figure 11 showing portions which control movement more particularly of the jack positioning or conditioning devices in widening and narrowing for fashioning;

Figure 15, a transverse vertical section on the line 15—15 of Figure 11 showing portions which control movement more particularly of decking, rack skip, and thread change devices in widening and narrowing for fashioning;

Figure 16, a transverse vertical section, enlarged, on the line 16—16 of Figure 3;

Figure 17, an enlarged fragmentary transverse vertical section across the needle bed portion including the stitch cams and associated parts;

Figure 18, a portion of Figure 16 further enlarged to more clearly show parts of needle jack conditioning devices;

Figure 19, a view partly in longitudinal vertical section on the line 19—19 of Figure 18 and with portions broken away and with parts removed;

Figure 20, a horizontal section on enlarged scale on the line 20—20 of Figure 18;

Figure 21, a horizontal section on enlarged scale on the line 21—21 of Figure 19;

Figure 22, an enlarged plan view of parts of the left end portion of the machine with some parts removed and some broken away;

Figure 23, a fragmentary view in vertical section on the line 23—23 of Figure 22;

Figure 24, an enlarged side view with portions broken away of an improved decker point;

Figure 25, an enlarged fragmentary top plan view of said decker point;

Figure 26, an enlarged front elevation with parts in longitudinal vertical section and other parts broken away to show more clearly jacquard shaft actuating and pattern control devices at the end of the machine shown in Figure 22;

Figure 27, a transverse vertical section on the line 27—27 of Figure 26;

Figure 28, a transverse vertical section on the line 28—28 of Figure 26;

Figure 29, a graph of the in and out motions of the front push-in bar and of movements of the adjustable controlling cams into and out of operation for one decking cycle wherein the operative position of the adjustable controlling cam for jacquard change (dotted lines) is maintained for

an extended period in decking (broken lines). Movement of the push-out bar is shown superposed on the out movement of the push-in bar during decking;

Figure 30, a fragmentary view showing the positions of a needle and a decker point in relation to each other and to the front and rear bed combs when the decker point is about to engage the needle in advanced position of the latter in decking;

Figure 31, a fragmentary view of the parts shown in Figure 30 when the decker point is about to receive the stitch loop from the needle in decking; and

Figure 32, a diagrammatic view of the decker or cam shaft and the cams actuated thereby.

Decking

The decker mechanism of the type shown in the accompanying drawings comprises devices for removing or casting off stitches from predetermined needles in the front bed, transferring said stitches laterally, and placing them on other selectively conditioned needles. Although the decker mechanism is described herein as operating on edge needles, as in fashioning for example, it is contemplated that parts thereof may also be employed in knitting lace designs, eyelet effects, feathered designs and cable stitch effects.

Instrumentalities provided for selecting and positioning said predetermined edge needles for decking, include the lifting plates 345 and 346, the fashioning bar 341, and slide rods 350 and 351, Figures 18, 19 and 21; and, for idling or activation, respectively, in fashioning include the narrowing or idling cams 311 and 313 and the widening or activating cams 312 and 314, Figures 18 and 20, and parts operatively associated therewith, as the slide rods 321 and 322. These instrumentalities cooperate with a main jack 293, a connecting jack 294, an interposed jack 295, and a cross jack 291, operating as a set, to condition each push jack 193 whereby the corresponding needle is selectively positioned for decking, as well as for other purposes, through its needle positioning jack 28 and suitable actuating devices, as the push-in bar 195.

The selection and conditioning of the push jacks 193 which control the operative position of those predetermined needles from which the stitch loops are to be cast off, in a given decking operation incident to narrowing, is accomplished by actuating the lifting plates 345, 346 during the pattern or jacquard change phase of the last knitting cycle preceding the decking cycle in which the stitches are cast off.

In the casting off or decking cycle, the selected needles are advanced to straight knitting condition where their hook portions are engaged by the decker points. Said loops are left on said points when said needles and their push jacks are retracted by push out bar 715, Figures 16 and 22. In the jacquard change phase of this cycle, the push jacks of the next active adjacent needles to which the cast off stitch loops are to be transferred are selectively actuated to condition said needles to receive said loops; and the narrowing mechanism operates to condition the push jacks of the needles from which the loops were removed to idle said needles in the next knitting cycle. During the decking cycle, knitting movement of the stitch cams 34, 35 on rods 40, Figures 16 and 17, and of the thread carriers 19 and brushes 21 is arrested.

In this decking cycle, only needles in the front

bed selectively conditioned by the lifting plates 345, 346 when the latter and connected parts are actuated to intermediate or straight knitting position by selector bar 502, Figure 18, are initially advanced by operation of the push-in bar 195. Said push-in bar actuated by cam 228, Figure 26, and associated parts, moves said needles in the front bed toward the rear bed and into loop lifting position in proper synchronized relation with the decker points 182, Figure 16, which are simultaneously moving forward and down toward said needles.

The latches of said needles are opened by the stitch loops suspended thereon, as the advancing inner ends or hooks of the needles move out of the front bed and past adjacent comb portions of the rear bed to their "in" position, as seen in Figure 30, or to the same extent as if advanced for straight knitting operation.

The advanced hooks of said needles with latches open are engaged at said "in" position by the decker points 182, after which, said needles are returned, or moved outwardly, by push-out bar 715 engaging end butts 29 of the corresponding needle jacks 28, to their normal retracted position, Figures 17 and 29.

Said decker points, while engaging said hooks, are simultaneously moved therewith from the position shown in Figure 30 to the stitch loop receiving position, about as shown in Figure 31, which is reached toward the end of said combined movement of the needles and the decker points 182. Said points thereupon move into the stitch loops as the latter are intercepted and cast off of the withdrawing needles by adjacent comb portions of the front bed. The decker points carrying said loops are then raised to clear the comb.

During said decking cycle, the selecting or jacquard change devices and the widening and narrowing control devices operate to determine the new number of active needles to be actuated in the next course by the knitting cams. The decker points are then moved laterally to present the removed loops in position to be received on the hooks of the selected active needles after narrowing has been effected.

When the decker points with the removed stitch loops thereon are moved to position with said loops opposite the inner ends of the selected active needles upon which said loops are to be received, the front push-in bar 195 brings all the active needles toward thread receiving position. For this purpose, and as indicated diagrammatically in Figure 29, a special "in" motion is imparted to the front push-in bar 195 by operation of cam 230, Figures 26 and 28. Said "in" motion starts near the end of the decking cycle and continues into the initial portion of the next knitting cycle. Said "in" motion begins earlier but proceeds more slowly than the corresponding "in" motion of said push-in bar 195 produced by cam 228 to advance the needles for a normal knitting course. The advancing hooks of the loop receiving needles are, therefore, pushed slowly and smoothly into engagement with said decker points and through said stitch loops suspended thereon.

To produce the "in" motions above referred to, said fixed cam 228 and said adjustable cam 230 cooperate with a cam roller 223 on the inner arm 225 of cam actuated front rocking levers pivoted at 220 at each end of the needle bed portion of the machine. The upper end of the outer arm 219 of said levers is operatively connected to actuate the front push-in bar 195, Figure 28. Said cam

228 is fixed on a sleeve 226 secured to shaft 9, Figure 26. Cam 230 is slidably mounted on said sleeve 226 and forms part of an assembly of cams which are adjustable inwardly against resistance of spring means, not shown, by arms 238 and 239 mounted on rock shaft 240, Figures 26 and 27 and which engage lugs 237 of a pressure ring 236 slidably mounted on shaft 9.

With the parts disposed as shown in Figures 26 and 28, cam 228 controls the swing of arm 225 of the front rocking lever and consequently the "in" motion of bar 195. When ring 236 is moved inwardly (right Figure 26) by arms 238 and 239, cam 230 is brought opposite cam roller 223 initially and as a part of each jacquard change and decking phase through operation of an arcuate cam 248 engaging cam roller 249 on arm 250, Figure 27, said cam 248 being actuated from the jacquard control in a manner more fully described and claimed in my co-pending application Serial No. 531,764. For the special earlier starting and slower "in" motion of bar 195 occurring at the end of decking, cam 230 is held in said "in" position by operation of cam 273 which through cam roller 275 on arm 276 secured to said rock shaft 240 continues to hold said adjustable cam 230 in operative position after arcuate cam 248 has passed roller 249 on arm 250, as indicated diagrammatically in Figure 29.

During the loop transferring phase as last described, the decker points move rearwardly across the gap between the needle beds along with the advancing needle hooks engaged thereby, so that the suspended stitch loops are intercepted by comb portions of the rear bed, stripped from the decker points, and deposited on portions of the advanced needles aligned therewith.

Accelerated motion is imparted to swing the now free decker points upwardly and back out of the path of the brush and thread carriers; and normal knitting is resumed.

Knitting stopped during decking cycle

Details of mechanism for interrupting or skipping a knitting course while effecting the movements of parts during the decking cycle, as above described, are shown in Figures 4, 5, 6 and 7. For this purpose, a decker control shaft 750 carries a cam arm 751, Figure 7, which interrupts knitting during the period of one course and another arm 752, Figure 6, which simultaneously therewith, starts decker actuating cam shaft 274 and stops it at the end of the decking cycle. Said decker control shaft 750 is actuated from suitable pattern control mechanism which includes a control link 810, Figures 3 and 9, connected thereto by an arm 811.

To arrest knitting during the decking cycle, cam arm 751, when moved by rotation of shaft 750, cooperates with cam roller 753 to lift lever arm 754, which is normally biased to the inoperative position shown in Figure 7 by a spring 754a. The free end of lever arm 754, when so lifted, engages and depresses the spring biased rolling key 755 of a clutch which includes clutch plate 13, Figure 4, thereby disengaging cam shaft 9 and said clutch plate 13 keyed thereon, Figure 8, from clutch key carrier 14 and gear 12 secured thereto. This stops rotation of said gear 12, the bevel gear 15, and the stitch cam and thread carrier actuating countershaft 16, Figure 4. Interruption of knitting, as aforesaid, occurs when, by operation of the control devices or other suitable means, decker control shaft 750 is rotated a part turn counterclockwise, Figure 7. The same turn

starts operation of decker cam shaft 274 by lifting the free end of an arm 152, Figure 6, which is pivotally connected to a cam carrying, lever arm 756 by a link 757.

Starting and stopping decking cycle

As seen more clearly in Figures 4 and 5, which show details of parts of the devices for starting and stopping rotation of said decker or cam shaft 274, Figure 32, lever arm 756 carries a cam piece 758 having a bevelled edge portion 758a normally positioned in relation to a clutch device to maintain the decker shaft 274 disengaged from sprocket 722 which is loosely mounted on said shaft 274 and connected to be driven by chain 730 from shaft 6, Figure 6.

Said clutch device comprises a collar 759 fixed on shaft 274 and having a peripheral annular groove 760 and a transverse plunger slot opening at one end into said groove. A plunger 761 slidably mounted in said slot, is biased toward the right, Figure 5 by a spring 761a. Normally, the bevelled portion 758a of cam piece 758 rests in said annular groove 760 in position to engage a shoulder at one end of plunger 761 to hold the latter in retracted position in said slot. However, when cam piece 758 is raised out of said groove 760, said plunger 761 is spring pressed inwardly to bring its other end into engagement with a radial slot 762 in the hub of sprocket 722. The gear ratio of said sprocket in relation to sprocket 731 on shaft 6 is such that decker shaft 274 is thereby rotated a full turn while shaft 6 is making two full turns.

Decker frame and cams actuating same

A decker point carrying and actuating frame including a rock shaft 763 located below and to the rear of rear bed 27, Figure 16, and arranged parallel with decker shaft 274, is rocked forward and back at appropriate times by a pair of cams 765 keyed to said decker shaft 274, Figure 32, at spaced positions thereon and actuated in cooperation with other devices to be described. Decker point carrying portions of said decker frame, operating above the rear needle bed 27, are also rocked or tilted relatively to said frame and independently of its rocking movement by suitable connection with a pair of cams 764 carried in spaced relation on decker shaft 274.

Needle motion controlling cams

As shown in Figure 32, said shaft 274 also supports in addition to the two pairs of cams above mentioned, other devices related more particularly to mechanisms which effect needle movements. These include a pair of rear push-in bar controlling cams 766, Figure 28; and a cam carrier 273a, Figure 27, having the push-out bar actuating cam 768 at its outer side and the special "in" motion producing cam 273 at its inner side.

The rear push-in bar 191 is mounted on and moves forward and back with an oscillatable angle bar 192 secured on end bearing blocks 204, Figure 28, slidably mounted on the frame. Said angle bar 192 is biased toward its "in" position by tension springs 199, Figure 1, operating through bell crank levers 200 pivoted at 201 and links 202 pivoted at 203 to said end bearing blocks 204, one at each end of said angle bar 192. The heads of the adjusting bolts 205 bear against semi-cylindrical rocker or pivot blocks 206 carried at the upper ends of rear rocking levers 208. Each of said rocker blocks is positioned to pivotally engage a conforming recess provided in an

upper end portion of a rear rocking lever 208 at each end of the needle bed portion of the machine and on which is pivotally mounted a cam roller 209, Figure 28. Thus, said rear rocking levers 208 are also normally biased toward "in" position by the operation of said springs 198 and, in knitting, are periodically rocked to move said rear push-in bar 191 outwardly against resistance of said springs by cams 210 supported on shaft 9 in position to continuously engage rollers 209. Said periodic oscillation of rear push-in bar 191 is arrested by operation of cam 766 on shaft 274 which prevents said rocking lever 208 from rocking forward (clockwise, Figure 28) during a portion of the decking cycle, i. e. while selected end needles are being moved into stitch transfer position. This withholds said bar 191 from its normal inward movement which is not needed at this stage because the decker devices, such as those shown in Figures 16 and 22, cooperate only with needles in the front bed.

Rear push-in bar arresting cams

Said cams 766 engage cam rollers 767 on rear rocking levers 208, Figure 28, and, in operation, prevent said levers, and consequently the rear push-in bar 191, from moving inwardly when the front push-in bar 195 is actuated to advance the end needles selected for stitch transfer to operative decking positions, Figure 30.

Special in motion cam

The function of cam 213 extending inwardly from the inner face of cam carrier 273a, Figures 26 and 27, is to maintain the slideable cam assembly shown in Figure 27 in effective position for cam 230 thereof to produce the aforesaid special "in" motion of the front push-in bar 195, Figure 29, at the end of the decking cycle. Thereby all the active needles are advanced earlier and more slowly than for the usual knitting course, which insures that those at the edge selectively conditioned for the purpose will accurately and effectively engage the decker points and receive the stitch loops therefrom.

Push out bar and actuating cam

Said carrier 273a also has the push out bar actuating cam 768 extending outwardly therefrom and movable upon rotation of said carrier into and out of engagement with a cam roller 169 on a bell crank 770. As seen in Figure 22, one arm of said bell crank has a handle 771 and a socket 772. The rounded outer end of a plunger 773 engages said socket 772. The flat inner end face 774 of said plunger bears against the outer end of a "push-out" or draw bar 775 supported on and extending substantially the length of the front cam housing 36. Said bar is provided with sets of spaced slide plates 781 and 781a.

As shown in Figures 22, 23, said front cam housing 36 is provided with an oblique slot 776 to receive a pin 777 mounted on said slide plate 781a. A spring 778 connects pin 777 with a relatively fixed pin 779 mounted on said housing 36 and biases said bar 775 toward the retracted position shown in Figure 22.

The direction of movement of said bar 775 is determined by suitable devices including flanged guide plates 780 secured to and obliquely disposed on a portion of the under surface of the top wall of said housing 36. Each of said guide plates 780 is embraced by and between edge portions of said slide plates 781 and 781a on "push-out" bar 775.

Through the connections just described, spring 178 normally biases said "push-out" bar toward "in" position, Figures 16 and 22 and, solid line, Figure 17. However, when cam 768 engages cam roller 169 during rotation of decker shaft 274, or if bell crank 770 is actuated to like effect by hand, plunger 773 is thrust inwardly against tension of spring 778 and imparts oblique endwise and outward movement to "push-out" bar 775. The latter engages any jack end butts 29, Figure 17, which may be in its path; and, in moving outwardly to the dotted line position there shown, withdraws the corresponding needle jacks 28 and any needles thereby engaged to their initial retracted positions. This withdrawal of the selected edge needles in the decking cycle is timed to begin after the decker points have engaged the hooks of said needles, Figure 30, and after push-in bar 195 has started back toward its outer position, Figure 29. The stitch loops previously formed on said edge needles are deposited on said points as the needles and the points reach the position shown in Figure 31.

Motions of decker points

During that portion of the decking cycle in which the above described "in" movement by cam 228 and "out" movement by cam 768 of the selected edge needles are effected through the push-in and push-out bars respectively and other parts provided for that purpose, the decker points mounted on a decker frame are first brought forward simultaneously in all needle sections to engage the advanced hook portions of said needles, as 23, Figure 30. They then continue to move with retracting movement of said needles to stitch loop receiving position, Figure 31. The needles are further withdrawn to normal position to disengage the stitch loops; and the decker points with the loops thereon, are all simultaneously raised, moved laterally and lowered. Later, after the stitch loops have been deposited as previously described, said points are returned rearwardly to inoperative position.

Decker frame and decker point mounting

Means are provided to effect operation of the decker frame and the decker points 182 carried thereby in proper direction and in synchronized relation with the forward and back movement of the selected edge needles, Figures 16, 22, 30 and 31. Said decker points 182 are mounted in a point holder 183 secured at the outer end of a decker carrying member in the form of an arm 184. The inner end of said arm 184 has a slot through which a screw bolt extends to adjustably secure said arm on a laterally movable and tiltable nut assembly 185, two of which are provided, as a pair, for each needle section, Figure 22. In narrowing, the nut assemblies of each pair move toward each other and in widening, away from each other. And in decking, said nut assemblies are rocked or tilted both in relation to the frame and along with the frame to define the path of operative movement of the decker points mounted on said arms 184.

Endwise adjustment of decker point carrier on decker frame

Each of said nut assemblies includes a bushing mounted on screw shaft 186 and internally threaded to travel endwise along the left and right-hand threaded portions thereof when said shaft is rotated. Said screw shaft 186 is rotated by means including link shaft 645, Figures 1, 2

and 11, which rotates in one direction for narrowing and in the opposite direction for widening along with operation of narrowing and widening control mechanism. Screw shaft 786 is supported between and journaled in upper end portions of the several arms 787 forming part of the decker frame.

Shaft 645 is rotated without back lash by chains 421, 421a from spring connected sprockets 420, 420a, on shaft 375 which operates automatically in response to the same devices, including slide bar 403, that control operation of fashioning shaft 369, Figure 11; or which may be operated for some purposes by hand.

Said control devices also include the pawls 380 and 386, Figure 14, for controlling rotation of fashioning shaft 369, and pawls 381 and 389, Figure 15, for controlling rotation of decker control shaft 375. The latter pawls are mounted on lugs 379 and 390, respectively, which extend laterally, (right) Figure 11, from the sprockets 371 and 374 and are angularly spaced in the direction of rotation of said sprockets about 210° from similar lugs 378 and 387 extending laterally (left), Figure 11, from said sprockets 371 and 374 and carrying the pawls 380 and 386 respectively. Sprockets 371 and 374 are continuously driven in opposite directions by chain 372 from sprocket 373 on shaft 6, Figures 11 and 12.

As seen in Figures 11 and 15, slide bar 403 carries a block 402a on which are mounted gate pieces 407a, 408a, and 412a which correspond in function and construction to similar pieces, 407, 408 and 412, Figure 14, cooperating with said pawls 380 and 386 which are included in the narrowing and widening control devices. Said decker control pieces 407a and 408a are mounted to control the extent of opening of a long gap in the pawl guiding surface 413 of plate 415; and the other decker control piece 412a is positioned to control the short gap in the pawl guiding surface 414 of said plate 415.

Bar 403 is slideable endwise to and from different operative positions wherein one or another of said gate pieces 407a, 408a is brought into the gap of surface 413; or gate piece 412a is brought into the gap of surface 414, Figure 15.

The parts are so calibrated that an open short gap represents lateral adjustment of the decker point carrying arm 784 equivalent to the width of one needle slot; and an open long gap, two needle slots. Accordingly, when bar 403 is in a first operative or extreme left position, Figure 11, the long gap in 413 is closed by gate piece 407a and the short gap in 414 is open. This permits operation of pawl 389 counterclockwise to the extent of one notch. Decker point carrying arm 784 is, therefore, moved laterally on screw shaft 786, to the extent of one needle groove in widening, by equivalent rotation of shaft 375, link shaft 645, and screw shaft 786, Figures 1 and 2.

With bar 403 in second position, as shown full lines Figure 11, the long gap in 413 is full open and the short gap in 414 is closed by gate piece 412a. This produces lateral adjustment of decker point carrying arm 784 to the extent of two needle grooves in narrowing.

In the third operative position of slide bar 403, the short gap is closed and the recessed portion, 408b of gate piece 408a is in the gap of 413, which produces lateral adjustment of decker point carrying arm 784 to the extent of one needle groove in narrowing.

In the neutral or extreme right position of slide bar 403, gate piece 408a closes the long

gap in 413 and gate piece 412a closes the short gap in 414. In this position of said gate pieces no pawl is actuated and both shafts 369 and 375 remain at rest.

5 Slide bar 403 is moved endwise to and from said several positions by the yoke lever 405 secured at the upper end of vertical shaft 406, Figures 3 and 11, and actuated by any suitable means. In the illustrated embodiment, an arm 405a on the

10 lower end of shaft 406 is pivotally connected at its outer end with a link 802 which is actuated endwise to swing said arm 405a to and from different angular positions by automatic control means shown in part in Figures 3 and 10.

15 The previously described lateral adjusting movement of the nut assemblies lengthwise of the decker frame in fashioning serves to move the decker points from loop receiving to loop delivering position which, after delivery of the loops, becomes a new loop receiving position for the next decking operation in a subsequent course. Such adjustment, therefore, constantly maintains said decker points in loop receiving relation to the edge needles.

20 *Manual adjustment of decker points simultaneously with widening and narrowing devices*

Under conditions which require manual adjustment of the decker points 782 and other instrumentalities operatively connected therewith, lengthwise of the needle bed, shafts 369 and 375, Figure 11, are rotatable by hand. For this purpose, a hand wheel 369a is secured to an end portion of one of them, for example shaft 369, so that said shaft may be rotated at will in either direction when slide bar 403 is in neutral position. This directly controls the position of the fashioning devices.

25 40 Equivalent and simultaneous widening and narrowing adjustments of the decker point carriers and other devices are transmitted from said shaft 369 through sprocket 368 thereon to sprocket 391 and thus to chain 393 and shaft 375. Figures 11 and 13. For this purpose, said sprocket 368 is fitted with laterally extending lugs 368a and sprocket 391 with similar lugs 391a. The angular extent of said lugs and their relative arrangement on the respective sprockets is such that, at each rotation of shaft 369 in either direction there is a lag between the beginning of that rotation and the rotation of shaft 375. For example, with shaft 369 rotating in the direction of widening, it will turn to the extent of one notch, or the equivalent of movement of the widening devices to the extent of one needle, before shaft 375 begins to rotate for widening. Also, with shaft 369 rotating in the direction of narrowing, it will turn to the extent of two notches before shaft 375 begins to rotate for narrowing. Therefore, after any such rotation of shaft 369 by hand and before resuming power operation, said shaft must be reversed manually one notch on the notched wheel 416 for widening and two notches for narrowing. This adjustment brings the parts into proper operative relation for normal knitting procedure.

30 45 50 55 60 65 70 75 777 Manual operation of shaft 369 as above described is effected independently of rotation of main drive shaft 6, because the narrowing pawls 380 and 381 and the widening pawls 386 and 389 are maintained out of engagement with their respective ratchet wheels by the gates 408, 408a, 412 and 412a, with slide bar 403 in inoperative position.

"In" and "out" decker motion

Said nut assemblies 785 which, with the decker points 782, are adjusted endwise automatically or by hand along the screw shaft 786, as above described, also turn freely around and swing with said shaft 786 through a limited arc in decking. Accordingly, at all operative positions of said assemblies and, therefore, of the decker points 782 thereon, the free ends of said terminal members or arms 784 move in a predetermined path by means hereinafter described to carry said decker points 782 into and out of operative stitch loop receiving and transferring or delivering positions.

End and intermediate portions of said screw shaft 786 are journaled at and between upper end portions of the arms 787 which are keyed on rock shaft 763, Figure 16, of the decker frame. Said rock shaft 763 is journaled in bearings below and at the rear of the rear needle bed. As seen in Figure 16, said arms 787 are bent to bring their upper end portions and said screw shaft 786 above the level of said rear bed. Lever arms 788, also secured on said rock shaft 763 carry cam rollers 789 which ride on the peripheries of the cams 765 on decker shaft 274 where they are yieldingly held by springs 790 engaging arms 790a on shaft 763. Thus, the required "in" and "out" rocking or angular component of the decker point movement is imparted to the decker frame and thence to the decker points through said rock shaft 763 by rotation of the cams 765 on decker shaft 274.

Up and down motion of decker points

Said decker frame also carries devices which cooperate with other parts of the machine for producing an independent angular or vertical swinging or rocking component of the decking movement of the terminal members 784 and the decker points mounted at the free end portions thereof. For this purpose, Figure 16, cams 764 on decker shaft 274 engage cam rollers 791 on bell cranks 792 pivoted at 793 on one or more of the several arms 787 of the decker frame. A compression spring 794 bears against said bell crank 792 to maintain each said cam roller 791 in effective engagement with the periphery of its cooperating cam 764.

The upper end of bell crank 792, Figure 16, is provided with a yoke to embrace a pin 795 extending laterally from arm 796 secured on a rock shaft 797 which is journaled in aligned bearings provided by the several spaced arms 787 of the decker frame. Shaft 797 also has arms 798 secured thereto. The outer ends of said arms 798 support and are connected by a toggle rod 799 of rounded contour, Figure 22. An arm 800 extends rearwardly from each nut assembly 785 and has a yoke 801 which embraces said toggle rod 799 and is free to slide lengthwise of said rod with lateral movement of said nuts 785 and the members 784 on screw shaft 786.

Thus, when cam 764 rotates with the decker shaft 274, each bell crank 792 is rocked about pivot pin 795 on arm 787. This rocks arms 796, shaft 797, and arms 798; and swings the toggle rod 799 carried thereby through a short arc, as between the ends of the slot 799a in the web of an intermediate decker arm 787, Figure 16. No such slot is required in the end arms 787 because rod 799 does not extend through them, Figure 22. A corresponding swing is imparted simultaneously to the several arms 800 and their nut assemblies 785 at all operative positions of

the latter along screw shaft 786 to vary to angular position of said decker points 782 mounted at the outer end of arms 784 which rock with said nut assemblies 785.

Decker synchronized with other devices

It will be apparent that synchronization of movements of the decker actuating devices with certain parts of the machine is effected through 10 the conjoint operation thereof by said shaft 274. For example, decker shaft 274 not only actuates said cams 764 and 765, Figure 16, but also the cams 768 which operate the push-out bar 775; the cams 273, Figure 27, which maintain the cam assembly in operation for the earlier and slower "in" motion of push-in bar 195; and the cams 766 which arrest operation of the rear push-in bar 191 when the edge needles are being advanced in the decking cycle toward loop delivering position by push-in bar 195. And the devices actuated by the cams above noted are synchronized with the mechanism for arresting knitting by common connection thereof with drive shaft 6.

The decking devices and controls, as above described, are of relatively simple construction well adapted to operate with other automatic mechanisms as part of a full automatic flat links knitting machine. An advantage of the devices whereby the decker points are maintained at their proper positions in relation to the needles to be decked from is that they operate positively and accurately. Further, they combine effectively with devices for imparting to and fro and up and down movement of the decker points and insure precision in lifting the stitch loops and placing them on other needles.

Decker points

The decker points 782 are of the construction shown in Figures 24 and 25. Each comprises a shank with a butt 812 at one end and opposed tapered resilient tips or spring arms 813 extending from the other end and forming a longitudinal slot between them. The outer end portions of said arms are disposed at an angle to the inner or base portions thereof and are also directed inwardly toward each other to close the outer end of said slot. Said closed end is offset from the base portions of said tips.

50 Ordinarily, when the selected needles are moved in decking toward the rear bed to the position of initial engagement with the decker points, the last formed stitch loops resting under the needle latches of said needles are intercepted by portions of the rear bed comb. As the needle hook of one of these loop bearing needles continues to move into its rear bed slot, the arrested loop engages the needle latch and deflects it to open position, after which said loop slides 55 past the free end of the latch and rests upon a portion of the needle shank. As shown in Figure 30, when the decker point reaches needle engaging position, it is moved downwardly and readily engages the needle hook in the slot between said tips 813 regardless of whether the latch is down, i. e. closed, or rocked back to open position. As the needle returns into the front bed and the hook thereof passes ends of a portion of the front bed comb, the latch closes down over the ends 60 of said tips, (Figure 31). The needle is then further withdrawn into the front bed to its retracted or neutral position leaving the stitch loop suspended on the decker point.

Thereafter, the decker point with said loop suspended thereon is moved to a new position oppo-

site a needle upon which the loop is to be deposited. For this purpose, the decker point moves downwardly over the exposed hook of said needle in such a manner that the ends of tips 813 thereof come behind said hook. In so doing, said tips are spread apart to pass the latch if the latch happens to be down.

The decker point constructed as above described permits positive and rapid actuation of the needles and points both in removing loops from needles and in placing removed loops on other needles, since it is not essential to operation of the points that the latches be open or closed when the needles are in loop delivering or loop receiving position in relation to said points.

The above described mechanisms are also shown and described but not independently claimed in my co-pending application Serial No. 530,761 filed herewith and of which the present application is in effect a division. Said decker point construction is also described and separately claimed in my co-pending application Serial No. 574,451 filed January 25, 1945, divided out of this application.

I claim:

1. In decking mechanism for straight independent needle knitting machines, the combination of a decker frame pivotally mounted to rock to and from decking position and including a rock shaft and spaced arms each having one end secured on said shaft, a screw shaft extending between and journaled at the other ends of said spaced arms and having a threaded portion, decker point carrying means having parts engaging said threaded portion of the screw shaft and mounted to rotate co-axially therewith, means for rotating said screw shaft to move said decker point carrying means endwise thereof to and from different operative positions, means for rocking said rock shaft, and means for rotating said decker point carrying means around said screw shaft.

2. In decking mechanism for straight independent needle knitting machines, the combination of a decker frame pivotally mounted to rock to and from decking position and including a rock shaft and spaced arms each having one end secured thereon, means for rocking said rock shaft, a second shaft journaled at the other ends of said spaced arms, a decker point carrying member mounted concentrically with and rotatable on said second shaft and having a decker point supporting portion extending outwardly from said second shaft and a lever extending inwardly from said second shaft, means for tilting said decker point carrying member including portions pivotally supported on said spaced arms and portions which operatively engage free ends of said levers, and means for actuating said tilting means.

3. In decking mechanism for straight independent needle knitting machines, the combination of a decker frame, a screw shaft journaled thereon and having a right- and left-hand threaded portion, a decker point carrier rotatably supported on and concentric with said screw shaft and in threaded connection with the threaded portion thereof, means for rotating said screw shaft in one direction to move said decker point carrier in a narrowing sense, and in the opposite direction to move said carrier in a widening sense, and means for rotating said decker point carrier around said screw shaft.

4. In decking mechanism for straight inde-

pendent needle knitting machines, the combination of a decker frame, a screw shaft journaled thereon and having a right- and left-hand threaded portion, a pair of decker point carriers 5 rotatably supported on and concentric with said screw shaft, one of said carriers having a left-hand thread and the other of said carriers having a right-hand thread engaging said threaded portion of said shaft, means for rotating said carriers around said screw shaft, and means for rotating said shaft in one direction to move said carriers toward each other and in the opposite direction to move said carriers away from each other.

15 5. In decking mechanism for straight independent needle knitting machines, the combination of a decker frame including a rock shaft on which said frame is mounted, a decker point carrying member mounted to rock on said frame, 20 a cam shaft, a first cam thereon arranged and adapted to effect rocking movement of said rock shaft and said decker frame, and a second cam on said cam shaft arranged and adapted to effect rocking movement of said decker point carrying member in relation to said decker frame.

25 6. In decking mechanism for straight independent needle knitting machines, the combination of a decker frame including a rock shaft on which said frame is mounted, a screw shaft having a left- and right-hand threaded portion, a decker point carrying member mounted to rock on said screw shaft and having a portion in threaded engagement with said threaded portion of the screw shaft, a cam shaft, cam means on 30 said cam shaft arranged and adapted to effect rocking movement of said decker frame and of said decker point carrying member, and a link shaft operatively connected to rotate said screw shaft to effect movement of said decker point carrier to and from different positions along the length thereof.

40 7. In decking mechanism for straight independent needle knitting machines, the combination of a decker frame, a decker point carrying member pivotally mounted to rock thereon, a rock shaft journaled in said frame, a toggle rod supported on and in spaced parallel relation to said rock shaft, said toggle rod having a toggle connection with a portion of said decker point carrying member, a cam shaft, a cam thereon, and means operatively interposed between said cam and said rock shaft to effect rocking movement of said toggle rod and thereby of said decker point carrying member.

55 8. In decking mechanism for straight independent needle knitting machines, the combination of a decker frame, a decker point carrying member pivotally mounted to rock thereon, a rock shaft journaled in said frame, a toggle rod supported on and in spaced parallel relation to said rock shaft, said toggle rod having a toggle connection with a portion of said decker point carrying member, a cam shaft, a cam thereon, a lever arm secured to said rock shaft, a bell crank lever pivoted on said frame and arranged with one end operatively connected to an end of said lever arm, and a cam roller on said bell crank lever biased into engagement with said cam.

60 9. In a straight independent needle knitting machine provided with widening and narrowing devices and wherein decking is effected by decker devices to transfer one or more stitch loops from one or more needles at the edge of the work to one or more needles adjacent thereto, the combination of a shaft for actuating said widening

and narrowing devices, a second shaft for actuating said decker devices, means for rotating one of said shafts manually, and means operatively interposed between said shafts to impart rotative movement from one to the other thereof.

10. In a straight independent needle knitting machine having a main drive shaft, decking devices and a knitting cam, a thread carrier and a brush carrier which normally operate periodically to knit successive courses, the combination of a decker cam shaft for actuating said decking devices, a countershaft for actuating said knitting cam, said thread carrier and said brush carrier, clutch means operatively interposed between said decker cam shaft and said main drive shaft, other clutch means operatively interposed between said countershaft and said main drive shaft and a decker control shaft arranged and adapted to operate one of said clutch means and thereby to effect rotation of said decker cam shaft and to operate the other of said clutch means and thereby to arrest rotation of said countershaft during rotation of the decker cam shaft.

11. In a flat links knitting machine having decker devices, knitting cams, and a rear push-in bar which is normally employed to push active rear bed needles toward thread receiving position in advance of stitch forming movement of said knitting cams, the combination of rear push-in bar actuating means, a cam shaft, cam means thereon for actuating said decker devices, and cam means thereon operatively engaging a portion of said rear push-in bar actuating means to arrest operation of the latter during rotation of said cam shaft.

12. In a flat links knitting machine having decker devices and narrowing devices and whereby in edge needles are moved to loop lifting position and stitch loops are lifted therefrom by said decker devices and said edge needles are idled and other needles are moved into position both to receive said lifted loops from the decker devices and to receive thread for the next course, the combination of means for pushing needles toward said positions including a push-in bar, an adjustably mounted cam cooperating with said push-in bar during decking to move said selected needles to loop lifting position, another adjustably mounted cam cooperating with said push-in bar during decking to move said other needles to loop receiving and thread receiving position, a decker device actuating shaft, and means operatively connected to said shaft and operated by rotation thereof to maintain said second mentioned cam in needle moving position.

13. In a straight independent needle knitting machine having decker devices including decker points and devices for moving needles to and from decker point engaging position, the combination of a decker frame, a decker point carrying member tiltably mounted thereon, a decker point on said carrying member including opposed resilient tips of which portions are spaced apart to form a needle hook receiving slot, means for actuating said decker frame and said decker

point carrying member to move said slotted end of the decker point into stitch loop receiving engagement with hook portions of a needle when the latter is in decking position.

14. In a straight independent needle knitting machine having needles provided with end hooks and latches pivotally mounted thereon in operative relation to said hooks, devices for conditioning said needles for decking, the combination of a decker point carrier, a decker point thereon comprising opposed resilient arms with portions spaced apart and tip portions curved toward each other, and means operative in synchronized relation to said needle conditioning devices and arranged and adapted to move the tip portions of said decker point between said needle hook and the pivotal mounting of said latch to cause said tip portions of said decker point to pass the needle latch and embrace the hook of a needle in decking position.

15. In a straight independent needle knitting machine having needles provided with end hooks and latches pivotally mounted thereon in operative relation to said hooks, devices for conditioning said needles for decking, the combination of a decker point carrier, a decker point thereon comprising opposed resilient arms with portions spaced apart and tip portions curved toward each other, a cam shaft, cam means thereon arranged and adapted to move said decker point carrier in a direction to cause said tip portions of said decker point to pass the latch and embrace the hook of a needle when in decking position and to remove a loop therefrom, and cam means on said shaft cooperating with said needle conditioning devices to condition another needle for receiving said loop from said decker point.

16. In a straight independent needle knitting machine provided with narrowing devices, decker points, and means whereby some active needles are moved into position for cooperative action with said decker points and stitch loops on said needles are lifted therefrom by said decker points and said needles are conditioned for idling by said narrowing devices and other needles are moved into position to receive said lifted loops from the decker points, the combination of a push-in bar arranged and adapted to advance some of said needles into position to have loops lifted therefrom by said decker points and others of said needles to receive said loops from said decker points, a cam operatively connected to actuate said push-in bar to move needles into said position for cooperative action with said decker points whereby the latter lift stitch loops from said needles, an adjustable cam normally positioned out of operative relation to said push-in bar, means for moving said cam into operative relation to said push-in bar, a decker point actuating shaft, and means operatively connected to said shaft and to said adjustable cam and arranged and adapted to hold said adjustable cam in position to actuate said push-in bar whereby said other needles are moved into position to receive said stitch loops.

THOMAS S. HAYHURST.
